UNITED STATES PATENT OFFICE.

SISSAK K. OUZOUN-BOGHSSIAN, OF WASHINGTON, DISTRICT OF COLUMBIA.

WATCH-MOVEMENT CASE.

1,375,661.

Specification of Letters Patent. Patented Apr. 19, 1921.

Application filed November 20, 1920. Serial No. 425,352.

To all whom it may concern:

Be it known that I, SISSAK K. OUZOUN-BOGHSSIAN, a subject of the Sultan of Turkey, having declared my intention of becoming a citizen of the United States, residing at the city of Washington, District of Columbia, have invented certain new and useful Improvements in Watch-Movement Cases, of which the following is a specification.

This invention relates to improvements in watch-movement-cases, and more particularly to the class which are adapted to be used as small bracket-clocks or desk-clocks.

The object of this invention is to provide a watch-movement case which has the thickness or depth, size and shape of a small bracket-clock or desk-clock-case, which watch-movement-case of the invention is a combination of several collapsible parts fitted together by screws, and is adapted to fit and have secured therein a stem-wind watch-movement, on which watch-movement-case of the invention are provided means to actuate the winding and setting mechanism of the watch-movement, and in which watch-movement-case of the invention the watch-movement compartment of the case together with the winding means are removably secured to the front part of the watch-movement-case of the invention, so that a watch-movement of the same size and desired kind and quality, or a watch-movement fitted to a certain class of watch-case can be readily fitted and secured to the watch-movement-case of the invention at any time desired, and be used as a small bracket-clock or desk-clock.

The nature, characteristic features and scope of the invention will be more fully understood from the following description taken in connection with the accompanying drawings forming a part hereof and in which:

Figure 1 is a perspective view of the watch-movement-case of the invention, to which is fitted a stem-wind and stem-set watch-movement. Fig. 2 is a view in sectional side elevation of the watch-movement-case of the invention, being sectioned at the dotted-line 2-2 in Fig. 1, the collapsible front, middle and back parts of which are slightly separated from each other, and the sleeve, stem and crown of which are removed therefrom. Fig. 3 is a sectional plan view of the watch-movement-case of the in-

vention, being sectioned at the dotted line 3-3 in Fig. 1, which is taken on a larger scale, to show more clearly the details of the arrangements of the front part 6 of the watch-movement-case of the invention. Fig. 4 is a perspective view of a modification of the watch-movement-case of the invention, in which the top and the two sides of the watch-movement-case of the invention are covered with a metal covering, which is removably fitted by a set of screws. Fig. 5 is a view in sectional side elevation of another modification of the watch-movement-case of the invention, in which a wooden block is not used, and the three detachable parts are shown slightly separated from each other.

Similar reference characters refer to similar parts in all the figures of the drawings.

Referring specifically to the drawings, in Fig. 1, the front and back metal parts 6 and 7 and the wooden middle part 24 are fitted together by a set of screws 10 at the front and back faces. A stem-wind watch-movement 27 is fitted to the front part 6, over which is screwed and fitted the bezel 1. The crown 11 and a stem-sleeve and a stem are fitted to the case sleeve 12. The winding and setting mechanism of the watch-movement 27 is actuated by crown 11.

In Fig. 2, crystal 16 is fitted to bezel 1. The case 14 is removably fitted to the circular opening of the face-plate 6, over which casing 14 and to the flange 20 of the casing 14 is screwed and fitted bezel 1, thus removably securing the face-plate 6 between the casing 14 and bezel 1. The circular compartment 9 is adapted to have fitted and secured therein a watch-movement of the same size. The flange 8 holds the watch movement from being dropped into the case, and the watch-movement is secured in the circular compartment 9 by two case screws of the watch-movement. The extending part 4 of the casing 14 fits into the cave 17, of the wooden-block 24, and the case-sleeve 12 fits into the cave 25. The circular ring 18 of metal is removably fitted into the wooden-block 24. Over the circular opening 22 on the back-plate 7 is fitted the back-cover 23. The watch compartment 9, circular compartment 19 and the opening 22 communicate.

In Fig. 3, the crystal 16 is fitted to the bezel 1. The casing 14 is removably fitted into the circular opening of the face-plate 6, and the bezel 1 is screwed and fitted to

the flange 20 of the casing 14, thus removably securing the face-plate 6 between the casing 14 and the bezel 1.

In Fig. 4, the metal covering 31 is fitted 5 by a set of screws 10 over the wooden block 24 shown in Figs. 1 and 2.

In Fig. 5, the front part 6 and the back part 7 are telescopically fitted into the metal middle frame 32 by the parts 35, 35 of the 10 parts 6 and 7. A set of screw bars 33 secure the three parts 6, 32 and 7 together. The watch-movement casing 14, on which is provided the case-sleeve 12, is removably secured on the face-plate 6 by the screw-bezel 15 1 as shown in Fig. 3. The opening 15 is adapted to have fitted therein a sleeve and stem with a crown fitted thereon, which are adapted to actuate the winding and setting mechanism of the watch movement fitted 20 into the circular compartment 9. The circular compartment 9 is adapted to have fitted therein a watch movement of the same size. The shoulder 8 holds the watch-movement from being dropped into the case, and the 25 usual case-screws resting on the edge 4 secure the watch-movement in the case. The screw bezel 1 is fitted on the screw threaded part 20. The back-cover 23 is fitted over the circular opening 22 and on the part 21. 30 The opening 21 communicates with the watch-movement compartment 9.

Having thus described the invention what I desire to secure by Letters Patent of the United States and claim is:

35 1. A watch-movement-case adapted to have fitted and secured therein a stem-wind and stem-set watch-movement and therefore

to be used as a bracket-clock or desk-clock, said case comprising a front metal part, a middle wooden part and a back metal part 40 fitted together by screws, said front-part comprising a face-plate removably secured between a watch-casing and a bezel with a crystal, said casing having provided thereon a case-sleeve having fitted thereto a stem-sleeve, a stem and crown adapted to actuate the winding and setting mechanism of the watch-movement fitted in said casing, said back part comprising a back-plate with a circular opening therein covered with a 45 back-cover, said middle-block having therein a circular compartment fitted with a metal ring and communicating with said watch-compartment of said front-part and the circular opening of said back-part, all 50 substantially as set forth.

2. In a watch-movement-case of the character described, the combination of a front-part with a detachable watch-movement compartment, with a case-sleeve provided thereon, said front-part comprising a front-plate, with a circular opening, removably secured between a watch-movement casing and a bezel with a crystal, the back-part of said casing fitting in an indentation provided on 60 the front part of a wooden middle-block, the winding and setting mechanism of said watch-movement being adapted to be actuated by a stem, sleeve and crown fitted to said case-sleeve of said watch-casing, all 65 substantially as set forth.

In testimony whereof I affix my signature.

SISSAK K. OUZOUN-BOGHSSIAN.
